Inventor:
B. V. Stoll
by Lucy, Lacey, his wife,

UNITED STATES PATENT OFFICE.

BERRY V. STOLL, OF LOUISVILLE, KENTUCKY.

PROCESS OF REFINING OIL.

Application filed October 28, 1919. Serial No. 383,976.

To all whom it may concern:

Be it known that I, BERRY V. STOLL, a citizen of the United States, residing at Louisville, in the county of Jefferson and State of Kentucky, have invented certain new and useful Improvements in Processes of Refining Oil, of which the following is a specification.

This invention is a process of the refining 10 of oil and relates more particularly to an improved process of "cracking".

"Cracking" processes are based on the well-known natural law that complex hydrocarbons, under certain temperature and 15 pressure conditions will decompose or split up into their component elements which will again unite to form different arrangements of their atoms and thus produce hydrocarbons of lower order and possessing different physical properties and differing in 20 their chemical structure. Thus in the refining of oil, when hydrocarbons of the C_nH_{2n+2} group or similar groups are subjected to a pressure of from two to three 25 atmospheres and to a temperature of from 650° F. to 1000° F. this natural decomposition takes place and the hydrogen and carbon atoms are rearranged, the proportion of hydrogen increasing and the proportion 30 of carbon decreasing. This naturally results in the release or formation of free carbon which in other "cracking" processes has been of great detriment. Therefore one 35 of the primary objects of the present invention is to evolve a process of "cracking" in the carrying out of which there will be practically no formation of free carbon as such so that this disadvantage of the heretofore practiced processes of "cracking" 40 will be overcome and there need be no interruption of the process for the purpose of cleaning the stills or other parts of the apparatus as has heretofore been necessary in 45 order to remove the accumulation of free carbon.

Furthermore in the "cracking" processes heretofore followed it has been necessary to redistill or rerun the crude product of the process in order to obtain a suitably refined product. The present invention therefore has as its object to evolve a process of "cracking", the product of which is a finished one, for example benzine, and requires no refining or other treatment to render it 50 fit for use.

I have discovered that if in the refining process the "cracking" takes place in the presence of steam, little or no free carbon will be formed and my invention is based on this discovery and contemplates the utilization of the same in a manner which will reduce the formation of free carbon to the minimum if not entirely eliminating its formation, and which will not in any way impair the completeness of the "cracking" of the crude product and which will result in a much sweeter product than can be obtained by other previously followed methods.

In order that the invention may be fully 70 understood, I will first describe a preferred form of apparatus for carrying out the process, and will then fully describe the process per se.

In the accompanying drawings: 75
Figure 1 is a view illustrating in a general manner the apparatus;

Fig. 2 is a vertical longitudinal sectional view through the still of the apparatus;

Fig. 3 is a vertical transverse sectional view on the line 3—3 of Fig. 2.

In the drawings the numeral 1 indicates a coil furnace which may be of any suitable construction and of any desired size and within which is arranged a pipe coil 2 through which the petroleum or crude oil is continuously forced under pressure by means of any suitable pump indicated in general by the numeral 3, a pipe 4 leading from the pump to the coils for conducting the oil to the said coils. A pipe 5 leads from the upper end of the coils 2 to the exterior of the furnace and, in a manner which will be presently described, is arranged to discharge 90 into the still which is indicated in general by the numeral 6. A thermometer 7 is interposed at a suitable point in the length of the pipe 5 as is also a pressure gage 8 and a pressure control valve 9, this latter being capable of being adjusted to open at a predetermined pressure which will be registered by the gage 8, and the coils 2 within the furnace being heated so as to maintain the oil circulating through the coils and the pipe 5 at a predetermined pressure and temperature recorded by the gage 8 and thermometer 7.

The still is preferably of the construction shown in Fig. 2 of the drawings and the same comprises a drum or cylindrical body 105 arranged within a suitable furnace indi- 110

cated in general by the numeral 11 and which is constructed and so fed as to maintain the still at a uniform and relatively low degree of temperature. The pipe 5 enters the drum 10 through the upper side thereof preferably adjacent the forward end of the drum and communicates with a head 12 having a number of downwardly projecting nozzles 13 through which the oil from the coils 2 may issue in fine streams or jets. A steam supply pipe 14 provided with any suitable type of control valve 15, is led through the forward end of the drum 10 and has a branch 16 which communicates with a head 17 corresponding to the head 12 and provided with upwardly projecting nozzles 18 equal in number to the nozzles 13 and each located below and opposite a respective one of the said nozzles 13 so that jets of steam issuing from the nozzles 17 will meet and impinge against the jets of oil issuing from the nozzles 13. A branch pipe 19 also leads from the steam supply pipe 14 within the drum 10 and communicates with a pipe 20 which extends longitudinally of the bottom of the drum and is provided in its opposite sides with series of perforations 21 through which steam will issue in small jets, as most clearly shown in Fig. 3 of the drawings, and sweep over the interior of the wall of the drum at the lower side thereof so as to prevent burning or scorching of the oil and buckling of the wall of the drum.

The lighter or vaporized products of the "cracking" and distilling process are carried off through a pipe 22 which leads from the top of the drum 10 of the still to a condensing coil or worm 23 located within a cooling tank 24 and provided with an outlet pipe 25 designed to discharge into a tank or other receptacle 26. A pressure controlled valve 27 is interposed in the pipe 22 as is also a pressure gage 28. A thermometer 29 is preferably arranged upon the front of the drum 10 of the still. The heavier or residual products of the process may be drawn off from the still through a pipe 30 which leads from the bottom of the drum, a suitable cut-off valve 31 being provided in this pipe.

In the operation of the apparatus and in the carrying out of the process of the present invention, the crude oil is forced by the pump 3 into the coils 2 under a pressure of approximately one-hundred pounds to the square inch, this pressure being indicated by the gage 8 and maintained by the pressure control valve 9 which is adjusted to remain closed until the pressure in the coil system equals that stated. The fire in the furnace 1 is controlled so as to maintain the oil in the coils 2 at a temperature of approximately 700° F. which temperature may be read upon the thermometer 7. From the coil system, the oil at the temperature and pressure above noted, which are sufficient for "crack-

ing" of the oil, is conducted through the pipe 5 to the still and is discharged into the drum 10 where it suddenly expands in the presence of a lower temperature. As an example, the fire in the furnace 11 will be so controlled as to maintain the still at a temperature of between 400° F. to 500° F., this temperature being suitable for the distillation of benzine. The pressure within the still is kept at approximately eighty pounds per square inch which will be indicated by the pressure gage 28 and maintained by the pressure controlled valve 27. As before stated, as the hot oil issues in streams or jets from the nozzles 13, these streams or jets are met by the jets of steam issuing from the nozzles 18 so that the jets of oil are broken up and the greater part of the oil vaporized, the heavier content falling to the bottom of the drum 10 from whence it may be drawn off through the pipe 30 whenever required. The vaporized products are as before stated carried off through the pipe 22 and are condensed in the condensing worm or coil 23.

From the foregoing it will be seen that the process involves the heating of the crude oil to a "cracking" temperature under a "cracking" pressure without at this point actually effecting a distillation of the lighter content of the crude oil, and the discharge of the oil into the still at a lower temperature and pressure to provide for sudden expansion which takes place in the presence of steam and during which period the "cracking" of the oil is effected. I may say that in evolving my process I tried the expedient of injecting steam into the oil during the passage of the latter through the heating coils but failed to obtain as large a percentage of light distillates as without the employment of steam although there was a considerable reduction in the amount of free carbon formed. Likewise in operating without steam I obtained an increased percentage of light hydrocarbons but experienced great difficulty on account of the large amount of free carbon formed and also the odor of the product, it having been necessary in fact to repeatedly interrupt the process in order to clean the accumulated carbon from the still. In my final efforts, however, as exemplified by the process as heretofore described, I discovered that there was practically no free carbon formed and that there was no appreciable decrease in percentage of the light hydrocarbon distillate obtained from a given volume of the crude product. I also found that by this process I could obtain a sweet product which did not require to be redistilled or subjected to any other sweetening process. In fact I found that because of the sudden expansion of the crude oil under a "cracking" temperature and pressure to a lower temperature and pressure, I could obtain an

increased percentage of light hydrocarbon distillate from a given volume of the crude oil.

It would seem reasonable to assume inasmuch as by effecting the "cracking" of the oil in the presence of steam, practically no free carbon is formed in this step the steam is decomposed into its elements, the hydrogen combining with the members 10 of the C_nH_{2n+2} group and the oxygen uniting with the nascent carbon as it is separated out of the members of the C_nH_{2n+2} group, to form members of the CO and CO_2 groups.

It is to be understood that while the 15 oil is cracked at the moment of its entrance into the still 6, this still does not truly constitute a cracking still but is more strictly speaking a sweetening still.

Having thus described the invention, what 20 is claimed as new is:

1. The process of refining oil which comprises subjecting the oil to a "cracking" temperature at a pressure of approximately one hundred pounds per square inch, and 25 allowing the same to expand under lower cracking temperature conditions and at a

pressure of approximately eighty pounds to the square inch, in the presence and subject to the atomizing and decarbonizing action of steam.

2. The process of refining oil which comprises subjecting the oil to a "cracking" temperature at a pressure of approximately one hundred pounds per square inch, allowing the same to expand under lower temperature conditions and at a pressure of approximately eighty pounds to the square inch, and atomizing the oil by means of steam at the moment of its expansion.

3. The process of refining oil which comprises subjecting the oil to a temperature of approximately 700° F. and a pressure of approximately one hundred pounds per square inch, and allowing the same to expand at a temperature of approximately 40 between 400° F. and 500° F. and a pressure of approximately eighty pounds per square inch in the presence and subject to the atomizing action of steam.

In testimony whereof I affix my signature.

BERRY V. STOLL. [L.S.]
